W. F. PAGEL,
PLUMBER'S TORCH,
APPLICATION FILED SEPT. 25, 1920.

1,409,232.

Patented Mar. 14, 1922.

UNITED STATES PATENT OFFICE.

WILLIAM F. PAGEL, OF SYCAMORE, ILLINOIS.

PLUMBER'S TORCH.

1,409,232.

Specification of Letters Patent. Patented Mar. 14, 1922.

Application filed September 25, 1920. Serial No. 412,643.

To all whom it may concern:

Be it known that I, WILLIAM F. PAGEL, a citizen of the United States, and a resident of Sycamore, in the county of De Kalb and

5 State of Illinois, have invented certain new and useful Improvements in a Plumber's Torch, of which the following is a specification.

10 My invention relates to improvements in heating devices and has special reference to improvements in so-called plumbers' torches, particularly the burners for such torches.

15 Usually such a torch comprises a tank for containing liquid fuel such as gasoline, means such as an air pump for placing the fuel under pressure, and a burner above the tank connected with the lower portion thereof to which the fuel is lifted by the pressure in the tank.

20 While the fuel for such torches was high grade gasoline very little difficulty was experienced in obtaining satisfactory results, but as the grade of the fuel constantly dropped more and more, difficulty has been 25 experienced in keeping the open flame burning satisfactorily, frequently the flame sputtering and going out on account of the projection of nongasified or liquid fuel through the burner, whereas the fuel should either 30 at the burner orifice, but preferably before reaching the orifice, be changed from a liquid to a gas.

35 My improvement contemplates the provision of such a perfectly operating gasifier through which the fuel passes on its way from the tank to the fuel orifice whereby, after the torch has been put in operation, it is a practical impossibility for any fuel to reach the fuel orifice in liquid form.

40 Another important feature of my invention relates to convenient means for the production of this effective gasifier; to means by which the passages can be readily cleared or cleaned; and to means for causing the 45 fuel to be gasified by heat derived from the flame of the torch.

Still further important advantages and features will be made clear from the following description, taken in conjunction with 50 the accompanying drawings forming part of this specification, and in which:

Figure 1 is a side elevation of a torch equipped with a burner shown in longitudinal vertical central section, and embodying 55 my invention in one form;

Figure 2 is a detail cross section of the

burner tube on the line 2—2 of Figure 1; and

Figure 3 is a section similar to Figure 1 showing a modified form of burner. 60

In said drawings, 1 illustrates the fuel tank of the torch or lamp, which carries at one side a hand operable air pump 2 for placing the liquid fuel in the tank under pressure. At the opposite side a pipe 3 is 65 secured to the tank by means of a pipe connection 4 at its lower end and a rigid bracket 5 affixed to the tank adjacent to its upper end. This pipe delivers the liquid fuel from the bottom of the tank to the burner, which 70 I designate generally by 6, above the top of the tank.

The burner comprises an elongated burner tube 7 which in common practice is inclined slightly upwardly toward its open end or 75 mouth 8. This tube is cylindrical in cross section and of substantially uniform diameter from end to end. The rear end is closed by a head or wall 9 which is provided with a central inlet opening 10 forming the inner 80 end of a hollow coned mixing tube 11 projecting rearwardly from the rear head 9 and axially with the burner tube.

Upon the under side of the burner tube I provide a nozzle 12 which is internally 85 threaded to fit upon the upper threaded end 13 of the feed pipe 3. The burner when screwed on to the feed pipe, is locked in position by a threaded hub 14 of a pan 15 which surrounds the tube 3 and is positioned 90 below the burner for use in heating same to start the torch.

For delivering the fuel from the feed pipe 3 to the burner I provide a feed passage 16 in the burner casting extending upwardly 95 from the hollow nozzle 12 into a horizontal feed passage or duct 17 which is arranged close to the lower wall of the cylindrical burner tube 7 and extends substantially the whole length of same. This duct is substantially horizontal, having the same pitch or inclination backward as the burner tube and the feed passage 16 enters substantially at the middle thereof. Between the nozzle 12 and the duct 7 I provide a needle shut off 100 valve 18 by which the flow of fuel to the duct 17 can be regulated or shut off. As shown in Figure 1, this valve 18 is formed on the inner end of a valve stem 19 which extends out through a suitable stuffer 20 and 105 is provided on its outer end with a suitable hand wheel 21. The inner end 22 of the

valve stem is threaded to fit in a threaded opening in the burner casting and by means of which the valve is adjusted in or out by being rotated. I arrange the valve stem 19 on an upwardly inclined angle so that the valve 18 can be positioned close to the feed passage 17 to reduce to a minimum the quantity of fuel which is left in the feed passages when the torch is stopped by shutting the 10 valve.

To deliver the fuel into the open end 23 of the coned mixing tube 11, I provide a delivery or feed pipe 24 which is U-shaped, having one long arm 25 adapted to be inserted within the duct 17 and a short arm 26 provided with a feed nozzle 27 adapted to be positioned centrally at the open end 23 of the mixing tube.

The feed pipe extends substantially the 20 whole length of the duct 17 and can be adjusted longitudinally relatively to the burner. It is adapted to be held fixed in its adjusted position by a stuffer nut or gland 28 through which the pipe extends and suitable packing 29 surrounding the pipe and 25 adapted to be compressed by screwing in the nut 28. This pipe is slightly smaller in diameter than the duct 17 providing a thin cylindrical space 30 surrounding the pipe 30 in communication with the feed passage 16.

The relatively thin film of fuel in the space 30 facilitates the changing of the fuel from a liquid to a gaseous form by heat derived from the burner 2. As the passage 35 30 is produced in the body of the burner casting the heat is readily transmitted through the casting from the burning gases within the burner tube to the fuel within the passage 30. As the liquid is gasified 40 it flows to the burner tip through the feed pipe 24.

In order that the inner end 31 of the feed tube 24 may not be accidentally closed or shut by pushing the tube in too far I 45 provide small notches 32 at the extreme inner end.

One advantage of the adjustable feed tube 24 is that the delivery orifice 33 of the feed nozzle 27 can be placed within the outer 50 end of the coned mixing tube, as shown in Figure 1. This prevents cross drafts or gusts of air blowing out the flame. The coned mixing tube, with the fuel nozzle at its outer larger end serves as an injector 55 to draw in sufficient air for proper combustion and the narrowing, or coned shape, assists in producing this suction effect and also assists in the mixing of the air with the stream of hot gaseous fuel issuing from the 60 fuel orifice. For the purpose of admitting additional fuel I provide holes 34 in the head 9 surrounding the inner end of the coned mixing tube 11.

While I have had excellent results with 65 a plain burner tube, I have found it ad-

vantageous to provide additional means for effecting the heating of the liquid fuel so as to assure its gasification even when extremely low grade fuel is used. For this purpose I provide an internal longitudinally extending rib 35 on the lower wall of the burner tube immediately above the passage 17 and adapted to project into the burner and absorb heat from the burning gases therein. This rib preferably extends substantially the 75 whole length of the passage 30 and conducts the heat absorbed from the flame, indicated by the dotted lines 36 to the wall of the burner tube and thence to the fuel in the passage 17. It is to be noted that from the 80 nozzle 12 to the fuel orifice 33 the fuel passages 16, 30 and the hollow feed tube 24 are of very small cross sectional area and that the heated portion thereof, both outside and inside the feed tube 24, is relatively long so that the interval of time to which the fuel is subjected to the heating effect is relatively long, thus assuring the perfect gasification of all of the fuel before it reaches the fuel orifice. The heat transmitted to the fuel by reason of the thin rib 31 which projects into the flame 36 is sufficient to assure the gasification of the fuel even if it is liquid fuel of the character of kerosene, or even fuel which requires a higher temperature than kerosene in order to gasify it.

In Figure 3 I have illustrated a form of burner which, while it preserves many of the important features of that shown in Figure 1, has some peculiar advantages of its own.

In this second form the burner tube 7, the feed passages 16 and 17, and the heat absorbing rib 35 are substantially the same 105 as shown in Figure 1.

In this form I do not provide a small feed tube which is readily longitudinally adjustable, but one which is fixed relatively to the burner tube once it is assembled. In this 110 form, however, as in that shown in Figure 1, the small feed tube is readily removable so that any clogging of the feed passages can readily be removed, but I eliminate the stuffer and packing which surround the 115 small feed tube in the first form.

In the second form I provide a feed connection 37 having an externally threaded end 38 adapted to be screwed into an enlarged end 39 of the feed passage 17 and provided with a small bore central feed passage 40. This connects with a feed tube 41 similar to the portion of the feed tube 24 lying within the passage 17 and having the same function of providing a thin film of 120 the fuel in contact with the metal of the burner and an elongated feed passage of small cross-sectional area.

The connection 37 is provided with an upstanding arm 42 provided on its free end 130

with a nozzle member 43 having a reduced fuel orifice 44 arranged centrally of the coned mixer tube 11.

The passage 40 connects the feed passage 5 through the feed tube 17 with a cross passage 45 leading up to the nozzle 43 and I provide a needle valve 46 in axial alignment with the passage 40 for shutting off and regulating the flow of fuel to the orifice 44. 10 As usual this valve is provided with a suitable hand wheel 47 and the stem of the valve is suitably packed to prevent the escape of fuel around same.

For clearing the delivery orifice I provide 15 a removable plug 48 at the rear of the nozzle 43. In this form of burner the fuel orifice is adjusted quite close to the inlet end of the mixing tube though on account of having to rotate the connection 37 to secure 20 it in position it is not practicable to position the delivery orifice within the outer end of the mixing tube. However, the shut off valve in this second form can be positioned closer to the delivery orifice and consequently 25 the quantity of fuel remaining between the valve and the orifice when the torch is shut down is less in the second form than in the first form.

As many modifications of my invention 30 will readily suggest themselves to one skilled in the art, I do not limit or confine my invention to the specific details of construction and arrangement of parts herein shown and described.

I claim:

1. In a plumber's torch, a tubular burner adapted to be connected with a fuel tank, a fuel passage communicating with the tank and having a fuel delivery orifice at one end of said burner, the fuel passage having a 40 portion within the wall of the burner, a feed tube of small diameter within said portion of the fuel passage, a valve for controlling the flow of fuel to the burner, and a rib on the inner surface of the burner adjacent to 45 said portion of the fuel passage, the rib adapted to project into the flame in the burner.

2. In a plumber's torch, a tubular burner adapted for connection to a fuel tank, means 50 for delivering fuel from the tank to a fuel orifice, comprising a passage at one side of the burner extending substantially the length thereof, a feed tube of relatively small diameter projecting into said passage 55 substantially the length thereof, and having a return bend portion provided at its free end with a delivery nozzle adapted to project fuel centrally into one end of the burner, said feed tube being longitudinally adjustable so that the nozzle can be projected within the adjacent end of the burner, and means for holding the feed tube in its adjusted position.

Signed at Sycamore in the county of De 65 Kalb and State of Illinois, this 21st day of September, A. D. 1920.

WILLIAM F. PAGEL.
